UNITED STATES PATENT OFFICE.

IRVING COWLES, OF CHICAGO, ILLINOIS.

VAPORIZING AND SPRAYING DEVICE.

Application filed April 5, 1922. Serial No. 549,942.

This invention relates to devices of the type designed to vaporize and spray the discharge from atomizers, engine primers, and similar instruments. The present invention is designed chiefly as a device for vaporizing and spraying into the intake manifold or cylinder of an internal combustion engine a previously prepared explosive charge of gasoline and air; but it will be apparent that the invention is capable of use in other situations and relations wherever it may be desirable to effectively vaporize and spray any liquid or semi-liquid material issuing under pressure from the distributing nozzle.

The common practice in vaporizing and spraying devices of this character is to provide in the spraying nozzle one or more fine holes or orifices which easily become clogged from foreign particles, verdigris, and corrosion, and are expensive to manufacture. The main object of the present invention is to provide a device free from the above named faults, which shall be easy and economical to manufacture, and which will deliver a continuous annular jet or spray controlled as to size and direction by the form and relation of the elements between which the annular delivery orifice is formed, and shall be self-flushing.

In the accompanying drawing I have illustrated two practical and approved embodiments of the principle of the invention, and referring thereto—

Fig. 1 is a side elevation of my improved nozzle shown as mounted in the wall of an engine manifold or other enclosed chamber designed to receive the spray;

Fig. 2 is a longitudinal section of the same;

Fig. 3 is a cross sectional detail on the line 3—3 of Fig. 1; and

Figs. 4, 5 and 6 are views corresponding to Figs. 1, 2 and 3, respectively, illustrating another form of the invention.

Referring first to Figs. 1, 2 and 3, 10 may designate a fragment of the wall of an intake manifold or of the head of an engine cylinder, in which is mounted a tubular coupling 11, one end of said coupling extending through the wall. In the opposite end of the coupling 11 is secured by a nut 12 one end of a pipe 13 leading from a pump, or other device which forms and delivers the explosive charge or other product to be delivered to and sprayed within the mani-

fold or engine cylinder. Within the other end of the coupling 11 is mounted and held therein by a tight fit or otherwise a section 14 of tube constituting the nozzle proper, which tube is closed at its outer end as shown at 15 in Fig. 2, and is formed just inwardly of its closed end with one or more radial passages 16, four such passages disposed at right angles to each other being 60 herein shown. Locked on the outer end of the nozzle 14, as by means of an annular key-groove 17 and a ring key 18 is a sleeve 19 formed with a concave inner end 20. Also slidably mounted on the tube 14 just inwardly of the sleeve 19 is a similar companion sleeve 21 having a concave outer end 22 opposite to and facing the concave inner end 20 of the sleeve 19. The sleeve 21 is backed by a light compression spring 23 encircling the tube 14 and abutting at one end against the sleeve 21 and at its other end against the inner end of the coupling 11. The spring 23 normally presses the adjacent 70 hollow ends of the sleeves 19 and 21 together, as shown in Fig. 1, thereby producing an annular chamber surrounding the outer ends of the radial passageways 16, with which hollow chamber said passageways freely communicate.

In operation, where the device is connected to the discharge line of a primer or like device, the explosive charge, flowing through the nozzle 14 under more or less pressure, is forced through the radial passageways 16 into the annular chamber between the two sleeves, this pressure forcing the rear sleeve 21 backwardly more or less against the resistance of the spring 23, as shown in Fig. 2, according to the pressure 80 of the charge and the resistance of the spring, thereby producing a continuous annular discharge orifice through which the charge is sprayed in a continuous film like annular jet of vapor which is picked up and 90 drawn into the engine cylinder on the suction strokes of the latter.

The annular chamber formed between the two sleeves insures the delivery of the charge in the form of a continuous annular jet, even though one or more of the radial discharge ducts should become clogged; such annular form of the jet insuring its most thorough and uniform dispersion 100 throughout the intake manifold.

The form of the invention shown in Figs. 4 to 6 inclusive is identical with that here-

inabove described except that the inner sleeve 21' is formed with an outwardly flaring flange-like extension 24 which overlaps the outer sleeve 19 and the annular discharge orifice of the annular chamber between the two sleeves, and has the effect of directing the annular jet of vapor inwardly or forwardly. This construction is preferably employed in all situations where it may be desirable to give a particular direction of movement to the annular jet upon its discharge. Obviously, wherever it is desired to give to the annular jet a direction other than a radial direction relatively to the discharge nozzle, this may be effected by arranging the extension 24 at the desired angle, or, in lieu thereof, locating a similar extension on the sleeve 19.

When the engine is running normally and drawing the fuel charges from the carburetor, the spraying nozzle is in the closed position indicated in Figs. 1 and 4, and no suction effect is produced on the primer or atomizer to which the nozzle is connected, if the primer or atomizer is sealed against the suction.

From the foregoing it will be manifest that the two sleeves function as a valve to give form and direction to the discharge from the radial ducts of the nozzle.

I have herein shown both sleeves as slidably mounted on the nozzle tube, this construction being preferred because of greater ease and economy of manufacture; but it is obvious that the outer sleeve 19 may be integral or fast with the nozzle tube without involving any change in the operation or efficiency of the device or any departure from the invention as claimed.

The distributor herein shown and described has been designed by me more especially for use in association with an auxiliary charge-forming device forming the subject matter of Letters Patent No. 1,572,381, granted to me February 9, 1926, which device is capable of being so manipulated as to function as an auxiliary carburetor before the engine is fully warmed up or is missing on account of a too lean mixture; and when so used, the sleeves 19 and 21 open under the suction of the intake manifold. This device is, however, by no means limited to its use with the particular charge-forming device mentioned, but may advantageously be employed with any other primer or charge-forming device, or in any other situ-

ation where a vaporizing or spraying device is used.

I claim:

1. A spraying and vaporizing nozzle of 60 the character described, comprising a tube closed at its outer end and formed with one or more lateral discharge passages, a pair of sleeves mounted on said tube and having their adjacent ends hollowed to form an annular chamber around said discharge 65 passages, and means for elastically pressing said sleeves together.

2. A spraying and vaporizing nozzle of 70 the character described, comprising a tube closed at its outer end and formed with a series of lateral discharge passages, a pair of sleeves mounted on said tube and having their proximate ends concaved to form an annular chamber surrounding said outlet 75 passages, one of said sleeves being locked against outward movement on said tube and the other slidably inwardly on said tube, and a spring urging said sleeves together whereby said chamber is normally main- 80 tained closed.

3. A spraying and vaporizing nozzle of 85 the character specified, comprising a tube closed at its outer end and formed with a plurality of lateral discharge passages adjacent to said outer end, an outer sleeve locked on the outer end of said tube, an inner sleeve slidably mounted on said tube, the proximate ends of said sleeves being concaved to form an annular chamber surrounding and opposite to the outer ends of 90 said discharge passages, and a compression spring mounted on said tube and urging said inner sleeve towards said outer sleeve, whereby said annular chamber is normally 95 closed and is adapted to be opened under internal pressure.

4. A spraying and vaporizing device of 100 the character specified, including a tubular nozzle closed at its outer end and formed with lateral discharge passages, a pair of sleeves mounted on said nozzle side by side and having their proximate ends concaved to form an annular discharge chamber, a 105 spring urging said sleeves into contact with each other to close said chamber, and a flange-like extension on one of said sleeves surrounding the joint between the latter and serving to give direction to the annular jet issuing from said chamber.

IRVING COWLES.
